(57) **CLAIM**

The ornamental design for a handle for a gas cutting torch, as shown and described.

DESCRIPTION

FIG. 1 is a top perspective view of the handle for a gas cutting torch;

FIG. 2 is another top perspective view thereof;

FIG. 3 is a right side view thereof;

FIG. 4 is left side view thereof;

FIG. 5 is a top view thereof;

FIG. 6 is a bottom view thereof;

FIG. 7 is a front view thereof; and,

FIG. 8 is a rear view thereof.

The broken lines are included for the purpose of illustrating environmental structure and form no part of the claimed design.

1 Claim, 8 Drawing Sheets

FIG. 2

FIG. 3

FIG. 4

FIG. 5

FIG. 6

FIG. 7

FIG. 8
